UNITED STATES PATENT OFFICE.

ADOLPH ADERER, JULIUS ADERER, AND HUGO ADERER, OF NEW YORK, N. Y.

DENTAL PLIERS.

SPECIFICATION forming part of Letters Patent No. 691,694, dated January 21, 1902.

Application filed April 11, 1901. Serial No. 55,279. (No model.)

To all whom it may concern:

Be it known that we, ADOLPH ADERER, JULIUS ADERER, and HUGO ADERER, citizens of the United States, residing at the city of New York, in the county of New York and State of New York, have invented certain new and useful Improvements in Dental Pliers, of which the following is a full, clear, and exact specification.

This invention relates to dental pliers; and its object is to construct improved pliers which shall be adapted for use in forming and shaping dental crowns. The method most generally employed in making these crowns is to first construct a die corresponding, particularly as to the grinding-surfaces of the tooth, to the desired crown and then to form a crown-blank upon this die. Our invention more particularly relates to an improved construction of pliers of the kind adapted especially to form and shape the crown and its grinding-surfaces or to re-form or reshape the same without the use of the die-plates and also adapted to conveniently change the shape of the surfaces of the crown when the latter has already been formed by the method above described.

The invention will be more particularly described with reference to the accompanying drawings, in which—

Figure 1 is a perspective view of a pair of pliers modifying our invention. Fig. 2 is a sectional view of the jaws, taken on the line *x x* and looking from the rear. Fig. 3 is a perspective view of a modified form of the pliers. Fig. 4 is a sectional view taken on the line *y y* in Fig. 3 and looking from the rear; and Figs. 5, 6, 7, 8, and 9 are perspective views of crowns in various stages of formation.

Referring more particularly to the drawings, 1 and 2 represent the respective jaws of the pliers, which are pivoted at 3 and moved by the handles 4 and 5 in the usual manner.

The jaw 1 projects forward beyond the jaw 2 and is pointed at its outer end. Its under side is provided with a slightly-curved or substantially flat surface 6. In the modification shown in Fig. 2 two flat surfaces 6 6 are formed for a purpose to be hereinafter referred to. The under jaw 2 is suitably curved, as at 7, in order to give sufficient clearance

for the band of the crown and meets the upper jaw at a pronounced angle thereto. Its extreme end 8 is rounded, and the rounded end impinges against the flat surface 6 when the pliers are closed. In the modification shown in Fig. 3 the two rounded surfaces 8 8 impinge against the respective flattened complementary surfaces 6 6.

In the operation of the device, assuming that a crown is to be formed, the usual blank crown, as shown in Fig. 5, is used as a basis for the crown. The pliers shown in Fig. 3 are used to form the biting-surface contours, and to do this the under jaw 2 is placed inside the crown, the point of jaw 1 reaching to near the center of the top of the blank. By forcing the jaw together the indentation 9 is made in the upper edge of the jaw and the raised portions 10 10 are formed on each side of the depression. At the same time the point of jaw 1 slightly depresses the center, as at 11. By repeating this operation upon the four sides of the crown the blank will be shaped substantially as shown in Fig. 6. If now this blank, with the biting-surfaces, needs reshaping—for instance, assume that one of the cusps 10 is too high and needs depressing—this may be done by substantially the same operation as heretofore described, but with greater pressure. In Fig. 7 the increased depressions are shown at 9 9. If the central depression 11 is not deep enough, this may be increased by using the pliers shown in Fig. 1, the rounded ends of jaw 8 being placed upon the top of the crown at 12 and the projecting jaw being inserted in the inside of the crown. Any or all of the various cusps or depressions may be removed by properly working upon the crown with the pliers shown in Fig. 1. For instance, the depression 12 may be raised by placing the rounded end 8 of the jaw on the inside of the crown and working the same into the shape shown in Fig. 9. In Fig. 9 the depressions 9 have been flattened out by operating the pliers with the rounded jaw 8 inside the crown. In like manner the crown may be formed or shaped in various ways by the use of the pliers herein described.

Having thus described our invention, we declare that what we claim as new, and desire to secure by Letters Patent, is—

1. A pair of pliers having two forming-jaws,

one of which is sharply bent for clearance and in such manner that it meets the other jaw at a point inside its extremity and at a pronounced angle thereto, said jaw having 5 a rounded end and said first-named jaw having a substantially flat under surface complementary to said rounded end, substantially as described.

2. A pair of pliers having two forming jaws 10 one of which is sharply bent for clearance and in such manner that it meets the other jaw at a point inside its extremity and at a pronounced angle thereto, said jaw having

two rounded ends, and said first-named jaw having two substantially flat under surfaces 15 inclining toward each other, said surfaces being complementary to the rounded ends, substantially as described.

In testimony whereof we affix our signatures in presence of two witnesses.

ADOLPH ADERER.
JULIUS ADERER.
HUGO ADERER.
